FIG. 1 is a front elevational view of a timepiece dial showing my new design indicating the time as three-fifty (3:50);
FIG. 2 is another front elevational view thereof indicating the time as twelve noon/midnight (12:00); and,
FIG. 3 is yet another front elevational view thereof indicating the time as one minute after twelve (12:01).
The dial is of no appreciable thickness and the rear is flat, plain and unornamented. The broken-line showings of a watch are environmental only and form no part of the claimed design.
